SWATTER GUN

John E. Kahler, Kankakee, Ill.

Application August 7, 1935, Serial No. 35,175

3 Claims. (Cl. 124—12)

This invention relates to an improved swatter gun, and seeks, among other objects, to provide a device of this character which may be used for quickly and effectually killing flies and other insects.

A further object of the invention is to provide a swatter gun having a relatively long barrel and plunger therein, which swatter gun may be employed for killing insects alighting in places impossible to reach with the well known screen variety of fly swatter.

Another object of the invention is to provide a device of this character employing a guard adapted to protect the swatter head employed against mutilation.

A further object of the invention is to provide a device of this character having a spring operated stem releasable by a trigger, said stem being adapted for engaging the plunger for forcing said plunger outwardly for engaging the swatter head with an insect.

A still further object of the invention is to provide a swatter gun, the plunger of which will be retracted by a spring surrounding said plunger, after a swatting operation.

And a still further object of the invention is to provide a swatter gun, the stem of which may be quickly retracted in proper position for releasing said stem by pulling the trigger.

Other and incidental objects of the invention will appear as the description of the invention proceeds.

In the accompanying drawing:

Figure 1 is a longitudinal sectional view of my improved swatter gun.

Figure 2 is a longitudinal sectional view, partly shown in elevation, and illustrating the gun as it would appear with the stem and trigger in proper position ready for a swatting operation.

Figure 3 is an enlarged fragmentary longitudinal sectional view on the line 3—3 of Figure 1.

Figure 4 is a plan view of a modified form of swatter head.

Figure 5 is a vertical sectional view of said modified swatter head.

Referring now more particularly to the accompanying drawing, wherein like numerals designate like parts throughout the several views, the numeral 1 indicates a preferably circular sheet metal gun barrel which is provided with an enlarged portion or breech 2 having a depending trigger guard 3, which trigger guard is extended rearwardly to provide a pivot mounting 4. Carried in the barrel 1 at its junction with the breech 2 thereof, is a wall 5 having an aperture 6 there-

in. The breech 2 is formed with an open end wall 7. Closing the outer end of the barrel 1 is a preferably metal cap 8 which may be screwed or otherwise secured to the end of the barrel. The cap 8 is formed with an aperture 9 axially thereof. The wall 5 is preferably held in place by tongues 10 struck inwardly from the barrel 1.

Associated with the barrel 1 is a stock or grip 10 which is pivotally connected to the breech 2 by a pin 11 extending through the pivot mounting 4. As best seen in Figures 1 and 2 of the drawing, the stock 10 is provided with a cut away portion 12 which is adapted to receive the pivot mounting and rearwardly extended portion of the trigger guard 3. The stock will be permitted to rock on the pivot mounting. Pivotally mounted within the breech 2 is a trigger 13 which includes a manually engageable portion 14 which extends into an opening 15 in the trigger guard. The trigger 13 also includes a socket or notch 16 which opens upwardly. The socket is formed by projecting a portion of the trigger forwardly in the breech 2 and upwardly, and, as best seen at 17 in Figure 1, the outer terminus defining the socket is rounded. The upper extremity of the trigger is adapted to engage the lower surface of the top wall of the breech 2 and is normally maintained thereagainst in position for cocking, by means of a coil spring 18. A pin 19 extends through side walls 20 of the breech and through the trigger for mounting the trigger, and the coil spring 18 is wound thereabout. Snugly but slidably mounted in the barrel 1, near the breech, is a stem 21 which is provided with a striking head 22. The stem 21 has its rear portion extending through the aperture 6 and bent downwardly to provide a stop 23, and is then bent upon itself upwardly and then again bent to define a hook 24 which is adapted to engage in the socket 16 when the device is cocked and ready for a swatting operation. A relatively large coil spring 25 surrounds the stem 21 within the barrel and between the striking head 22 and the wall 5. This spring normally maintains the stem in full extended position. A cocking yoke 26, preferably formed from a single strand of heavy wire, extends about the stop 23, extends throughout the length of the breech, and is connected with the inner end portion of the stock 10. It will be seen that when the stop 10 is rocked downwardly, the cocking yoke will be drawn rearwardly for retracting the stem 21 and engaging the hook 24 thereof in the socket 16, the wall 17 normally retaining the hook against displacement until the trigger is pulled. The cocking yoke may be cast

or stamped from a single piece of material, if desired.

Mounted in the barrel 1, forwardly of the stem 21 and head 22, is a plunger 27 which is provided at its inner end with a striking head or plate 28 adapted for striking contact with the striking head 22 of the stem 21. The plunger 27 is relatively long and is adapted to extend axially of the barrel throughout its length. Surrounding the stem 27 is a relatively light weight coil spring 29. The coil spring is maintained in position within the barrel by the cap 8 and the plunger 27 is adapted to extend through the opening 9 in said cap. As best seen in Figure 1 of the drawing, after the swatter gun has been set off and the stem is at rest, said stem will engage the plunger and force it outwardly a slight distance. However, as seen in Figure 2, when the device is cocked and the stem 21 retracted, the relatively light spring 29 will urge the plunger inwardly to its inward limit of travel. The plunger 27 will be limited in its inward travel by the inner extremity of the swatter head 30 which is secured to the outer end portion of the plunger 27. The swatter head is preferably formed from sponge rubber so that the scratching of furniture or other surfaces will be prevented. It should be understood that while I have shown the parts as being made of light weight metal, said parts 30 may be formed from wood, hard rubber, or a composition, as desired.

After the device has been cocked in the manner above described and it is desired to kill an insect, the barrel is pointed at the insect and the trigger is pulled. It is, of course, assumed that the device is held near enough to the insect so that the plunger will be permitted to strike it. As the trigger is released, the tension of the relatively heavy spring 25 will overcome that of the spring 29 as the head 22 contacts the head 28, so that the plunger will be suddenly forced outwardly with considerable velocity for engaging the swatter head 30 with the insect. In view of the fact that the swatter head is made preferably of sponge rubber, danger of crushing the insect against the surface on which it has alighted, with danger of marring thereof, will be largely eliminated.

Surrounding the end portion of the barrel is a relatively large circular guard 31 which is adapted to surround the swatter head 30 and protect it against mutilation when the device is not in use. The guard 31 may be made of sheet metal or other suitable material and may either be formed integral with the barrel or secured thereto in an appropriate manner. After a swatting operation, the spring 29 will retract the plunger and swatter head immediately so that the device, after cocking, will be ready for another operation.

Carried in the trigger guard 3 at its forward end is a block 32 of relatively soft rubber, which is adapted for engagement by the stop 23. The rubber block prevents the stem from suddenly contacting the end wall 5 and thereby prevents wear and possible mutilation.

Referring now to the modification of my invention as shown in Figures 4 and 5 of the drawing, the numeral 33 designates a circular swatter disc which is formed of rubber and is provided with projections 34. The disc 33 is also formed with openings 35 which, it is believed, will cut down air resistance as the device is being urged forwardly by the spring 25 of the preferred form.

This modified swatter disc, being formed of rubber, is particularly efficient as it may be readily

cleaned and, if so desired, may be made in a number of different designs and sizes. It is thought that this form of disc or head will be very durable in use. The disc is adapted for operation in an identical manner with that of the preferred form. 5

It is believed that, from a reading of the foregoing, it will be seen that I have provided a simple and highly efficient swatter gun which may be manufactured to retail at a reasonable price 10 and which will be durable over a long period of time. Children as well as adults will take a greater interest in the destruction of insects in view of the possibilities of skill in marksmanship offered by my device. 15

Having thus described the invention, what I claim is:

1. A swatter gun including a barrel having a breech, a stock pivotally connected with the breech, a wall between the barrel and the breech, 20 a stem slideable in the barrel and having an end projecting into the breech and bent to form a hook and a stop, a trigger having a socket adapted for removable engagement by the hook, a spring surrounding the stem within the barrel 25 forwardly of the wall, a cocking yoke connecting the stem with the stock, said cocking yoke being adapted to be rocked for retracting the stem and engaging the hook with the socket in the trigger, said stop being adapted to limit forward movement of the stem, a plunger in the barrel and movable independently of the stem, a swatter head on the plunger, and a relatively light spring surrounding the plunger within the barrel, said plunger being adapted for engagement by the 30 stem as the trigger and first mentioned spring are released for shifting said plunger against the tension of the second mentioned spring and forcing the swatter head into engagement with an object, said second mentioned spring being 40 adapted to retract the plunger after a swatting operation.

2. A device of the class described including a barrel having a breech formed with a trigger guard, a wall between the barrel and the breech, 45 a trigger in the breech and having a socket, a pin mounting the trigger within the breech, a stock pivotally connected with the breech, a stem slideable within the barrel and extending through the wall into the breech, said stem having its 50 inner end portion bent to define a stop and bent again to define a hook removably engageable with the trigger, means connecting the stem with the stock and adapted for retracting the stem as the stock is rocked, a striking head carried on 55 the stem, a relatively heavy spring confined between the wall and the head, a relatively soft block carried by the trigger guard and engageable with the stock for providing a forward abutment for the stem, a plunger slideable in the barrel and independently movable with respect to the stem, a striking plate carried by the plunger, a swatter head carried by the plunger, a cap closing the outer end of the barrel, a relatively light spring surrounding the plunger between the 60 cap and the striking plate, and a guard surrounding the outer end portion of the barrel and projecting forwardly thereof for protecting the swatter head at rest, said plunger being shiftable against the tension of the second mentioned 65 spring as the hook is released from the trigger and the stem is urged forwardly by the first mentioned spring whereby the swatter head will be moved forwardly for engagement with an object. 70

3. In a device of the class described, a barrel having a trigger guard, a resilient block carried in the trigger guard at its forward end and beneath the barrel, a stock hingedly connected with the barrel at its rear end, a stem carried in the barrel and having a stop and a hook, a cocking yoke connecting the stem and the stock, said cocking yoke being engageable behind the stock and said stem being retractable in the barrel as the stock is shifted with respect to the barrel, a trigger carried in the barrel and being mounted

to project into the trigger guard for manual engagement, said trigger being adapted to engage the hook after retraction of the stem whereby said stem will be held rearwardly in a cocked position, and means on the stock for urging the stem forwardly after release of the hook by shifting of the trigger, said stop being engageable with the resilient block for limiting forward movement of the stem. 5
